UNITED STATES PATENT OFFICE.

ALEXANDER JACKSON FIKE AND CHARLES MORGAN FIKE, OF CLIFTON MILLS WEST VIRGINIA.

PNEUMATIC HORSE-COLLAR.

No. 904,322.

Specification of Letters Patent.

Patented Nov. 17, 1902

Application filed May 13, 1902. Serial No. 432,717.

To all whom it may concern:

Be it known that we, ALEXANDER JACKSON FIKE and CHARLES MORGAN FIKE, citizens of the United States of America, residing at Clifton Mills, in the county of Preston and State of West Virginia, have invented certain new and useful Improvements in Pneumatic Horse-Collars, of which the following is a specification, reference being had therein to the accompanying drawing.

This invention relates to a pneumatic horse collar, and the object of our invention is, to provide a collar wherein compressed air is used as a cushioning medium for the collar, instead of a stuffing of hair, straw or similar material.

Our invention aims to provide a horse collar that will thoroughly protect a horse's neck, preventing sores, and sweating caused by a collar agitating the neck of a horse.

To this end, we have devised a collar having an inner tube conforming to the shape of the collar, said tube being filled with air under pressure to maintain the tube in proper shape, whereby it will fit upon a horse's neck and prevent the metallic or hard surface of the collar from contacting with the neck of a horse.

The detail construction entering into our invention will be presently described and then specifically pointed out in the appended claims.

Referring to the drawings forming a part of this specification, Figure 1 is an elevation of a horse collar constructed in accordance with our invention, partly broken away and partly in section. Fig. 2 is an elevation of a portion of the collar illustrating the metallic connecting means, Fig. 3 is a cross sectional view of a portion of the collar, Fig. 4 is a similar view illustrating the modification of our invention, and Fig. 5 is an elevation of one of the shields.

In the accompanying drawings 1 designates an inner tube, 2 a casing, 3 a metallic shield and 4 a hame support.

The inner tube 1 is made of rubber or resilient metal and conforms in shape to the ordinary horse collar, said tube having enlargements 5 connected by a neck 6 at the bottom of the collar, said enlargements gradually tapering to the top of the collar, where one end of the inner tube is provided with an inlet valve 7 of a conventional form. This valve permits of a pump being attached to

the inner tube to compress air therein similar to the pneumatic tire of a bicycle or automobile.

The casing 2 is formed with a pair of tubular portions separated by a contracted neck. 6 The tubular portions are of different diameters, that tubular portion of smaller diameter constitutes a hame support 4 and is stuffed with a suitable packing 8. That portion of larger diameter surrounds the inner tube 1 and protects the same from being injured or punctured. The portions of the material which form the contracted neck are secured together by the rivets 9. The rivets also connect the metallic shield to the casing 2. The shield 3 is of compound curvature so that it will abut against a portion of the casing which incloses the inner tube 1, also abutting against the contracted neck portion and extending partly over the hame 75 support 4. Additional rivets 10 are provided for securing the lower portion of the shield 3 to the tubular portion of greater diameter of the casing 2. The shield 3 is formed of two sections and the said sections 80 are connected at their lower ends by a link 11. This connection permits of the collar being easily placed upon the neck of a horse, the upper ends of said collar being connected together by straps 12 and a buckle 85 13, said straps being secured to the upper apertured ends of the shield 3.

The upper ends of the casing 2 are laced, as at 14 to retain said casing upon the inner tube 1.

In Fig. 4 of the drawings we have illustrated a modification of our invention, wherein the collar is formed of reinforced rubber or a similar material, the hame support 4 instead of being stuffed, is pneumatic, 95 similar to the remainder of the collar. The shield 3 prevents a pair of hames from injuring the collar, while the collar proper prevents a horse's neck from being injured.

While in the drawings forming a part of this application there is illustrated the preferred form of our invention, it is to be understood that the same may be varied as to the shape, proportion and exact manner of assemblage without departing from the 105 spirit of the invention.

Having now described our invention what we claim as new, is:—

1. A horse collar comprising an inner tube having enlarged portions connected by a 110

neck and having tapering closed ends, an air inlet valve carried by one end of said tube, a casing surrounding said inner tube and provided with means to constitute a hame support, metallic shields secured to said casing, and a metallic link connecting the lower ends of said shields, substantially as described.

2. A horse collar comprising an inner tube, a casing formed with a pair of tubular portions separated by a contracted neck, the said portions of different diameter, the larger inclosing said inner tube and the smaller constituting a hame support, a shield

formed of two sections, each of said sections 15 abutting against a part of said tubular portions and further abutting against said neck, means for connecting said sections to the neck, and means for connecting said sections to the said tubular portion of larger diameter. 20

In testimony whereof we affix our signatures in the presence of two witnesses.

ALEXANDER JACKSON FIKE.
CHARLES MORGAN FIKE.
